UNITED STATES PATENT OFFICE

2,359,663

SHOE MACHINE

Alfred R. Morrill, Beverly, Mass., assignor to
United Shoe Machinery Corporation, Flemington, N. J., a corporation of New Jersey

Application June 13, 1941, Serial No. 397,918

37 Claims. (Cl. 112—46)

The present invention relates to improvements in shoe sewing machines, and is herein shown as embodied in an inseam shoe sewing machine of the type in which the shoe is supported upon a jack, and in which the jack and sewing mechanism are moved relatively to transfer the point of operation about the shoe, and to change the relative positions of the shoe and the sewing mechanism to cause the shoe to be presented properly to the sewing mechanism as the point of operation is transferred about the shoe, all of the relative movements of the shoe and the sewing mechanism being produced and controlled by automatically acting mechanisms.

The invention relates more particularly to the development of an automatic inseam shoe sewing machine of this general type, in which is provided a chainstitch sewing mechanism comprising a curved hook needle arranged to enter the work from the sole side and to emerge through the upper or welt, so that the chain loops of the successive stitches are laid in the stitch receiving channel to form a so-called reverse or inside chain.

Certain features of applicant's machine relating particularly to the automatic work support and to the driving and stopping mechanism for the machine, form the subject-matter of applicant's copending application Serial No. 364,223, filed November 4, 1940, for Shoe machines, and are therefore herein referred to or illustrated only so far as is believed necessary to illustrate the connection of the present invention therewith.

Inasmuch as inseam sewing machines of the type in which the shoe is held by the operator and adapted for sewing a reverse chain are known in the art as exemplified by applicant's prior Patents Nos. 2,041,945 and 2,220,112, the sewing mechanism of the present machine is illustrated and described only so far as is believed necessary to present novel features of the present construction, and to enable one skilled in the art to adapt a sewing mechanism of this general type for use in an automatic machine provided with a shoe supporting jack and automatic means for imparting positioning and feeding movements to the jack to transfer the point of operation about the shoe.

It is an object of the present invention to provide an inseam shoe sewing machine having a curved hook needle arranged to enter the work from the sole side for the sewing of a reverse chain, of which the sewing mechanism and the work guiding and supporting instrumentalities

associated therewith are particularly constructed and arranged to cooperate with the automatic devices for imparting positioning and feeding movements to the jack supported shoe in such a manner as to insure the formation of regular properly placed stitches in the seam during the transfer of the point of operation about the shoe under the control of said automatic devices.

It is a further object of the invention to provide novel and improved means for holding and severing the thread in an inseam shoe sewing machine of which the curved hook needle is arranged to enter the work from the sole side for sewing a reverse chain. Specifically this object 15 contemplates the provision of a thread holding and severing mechanism adapted to cooperate with mechanism for severing and advancing the welt in a fully automatic reverse chain welt sewing machine provided with a shoe supporting 20 jack, and automatic means for imparting positioning and feeding movements to the jacked shoe to transfer the point of operation about the sole margin of the shoe.

It is another object of the invention to provide 25 novel and improved means for releasing and for re-establishing the tension on the thread operative in stopping the machine to release the tension on the thread and operative when the machine is started to re-establish said tension 30 only after a plurality of the initial stitches of the seam have been sewn.

It is another object of the invention to provide 35 in an inseam shoe sewing machine having a curved hook needle arranged to enter the work from the sole side for the sewing of a reverse chain, and cooperating thread finger and looper elements, of which the looper is provided with an open eye for ease of threading, and in which additional means is provided for maintaining a 40 sufficient friction on the thread to prevent the thread from becoming dislodged from the needle eye during machine operation and in the event of thread breakage to prevent the thread from being drawn backwardly through the machine.

45 With these and other objects in view as may hereinafter appear, a feature of the invention consists in the combination of an inseam shoe sewing mechanism including a curved hook needle arranged to enter the work from the sole side for the sewing of a reverse chain, with an automatic work support comprising a shoe supporting jack and pattern mechanism for imparting positioning and feeding movements to the shoe supported on the jack, of which the shoe sewing mechanism is particularly constructed and

arranged to cooperate with the pattern mechanism to insure a continuous and even feed of the shoe and the proper formation of the successive stitches of the seam in accordance with the dictation of the pattern mechanism.

Another feature of applicant's invention consists in the combination with the automatic work support, of an inseam shoe sewing mechanism having a curved hook needle arranged to enter the work from the sole side, and a work perforating awl disposed at the opposite side of the work from the needle, in which each of the needle and awl is arranged to move in the line of feed while engaged in the work, and in which both the needle and awl are withdrawn from the work during a portion of each stitch forming cycle to permit the positioning and continued feed of the shoe under the control of the automatic work support.

Another feature of the invention consists in the specific construction and arrangement of the sewing mechanism adapted for sewing a reverse chain in an automatic machine of the type described, with particular reference to the construction and arrangement of the channel guide which is mounted to move with the needle and awl in the line of feed to provide a more efficient support for the work against the strains exerted thereon by the stitch forming devices.

Another feature of the invention consists in the provision in an automatic reverse chain shoe sewing machine of the general type described, of a novel and improved thread holding and severing device which is actuated and controlled with relation to the several operating mechanisms of the machine to cut and clamp the thread at the end of the sewing operation, and to release the held thread end substantially at the completion of the first stitch of a new seam.

Other features of the invention relate to specific improvements in the sewing mechanism as hereinafter more fully set forth.

While the several mechanisms of the present invention are disclosed in connection with, and are particularly applicable to a fully automatic inseam shoe sewing machine adapted for sewing a reverse chain, certain features of the invention are capable of use in machines in which the shoe is held in position by the operator. It is to be understood that except as defined in the claims, the several features of the invention are not limited to the particular construction and arrangement of the parts.

The features of the present invention above referred to, and other novel constructions, combinations and arrangements of parts hereinafter described and claimed, will be apparent to those skilled in the art from the following description taken in connection with the accompanying drawings which illustrate an automatic welt shoe sewing machine provided with specific embodiments of the several features of the invention.

Referring to the drawings, Fig. 1 is a view in right side elevation of the machine, but with the jack removed; Fig. 2 is a view in left side elevation of the machine, but with a portion of the jack and its supporting spindle removed; Fig. 3 is a view in front elevation of the machine; Fig. 4 is a view in left side elevation showing substantially the head section of the machine housing the sewing and driving and stopping mechanisms; Fig. 5 is a sectional elevation taken through the head section of the machine, and looking from the right, to illustrate particularly the driving and stopping mechanism; Fig. 6 is a view in right side elevation, partly in section sub-

stantially on a line 6-6 of Fig. 7, illustrating substantially the parts housed in the upper part of the middle section of the machine including portions of the driving and stopping mechanism,

- 5 the drive to the pattern cam shaft, and the feed lever linkage connections; Fig. 7 is a sectional plan view taken on a line running generally between the head section and the middle section of the machine, illustrating substantially the parts shown in Fig. 6, and including additionally the stop motion eccentric and the trip mechanism for throwing the stop motion into operation; Fig. 8 is a detail view in front elevation illustrating particularly the trip mechanism for throwing the stop motion into operation, and the stop motion eccentric rock shaft, this figure showing substantially the parts illustrated in plan in Figs. 9 and 10, and in the assembly plan view Fig. 7; Figs. 9 and 10 are similar plan views of the mechanism shown in Fig. 8, the parts being shown in Figs. 7, 9 and 10 in a number of different operating positions, of which Fig. 7 shows the parts in their normal stop position ready for the starting of the machine, Fig. 9 shows the parts 20 in a position taken during stopping, the treadle latch bar having been withdrawn to put the stop motion in operation, the positioning lever for the auxiliary clutch control rod having been biased for movement forwardly or to the left from the position of Fig. 9, and Fig. 10 shows successive 25 positions of the eccentric driven rock shaft during operation of the eccentric, the full line position illustrating the control lever and auxiliary clutch control rod in their forward or operating 30 positions taken as the control rod is raised to establish an operating connection with the auxiliary clutch shifting lever, but with the eccentric controlled rock shaft in its starting position, and the dot-and-dash position illustrating 35 a subsequent position of the parts in which the eccentric has been rocked to the limit of its movement in a clockwise direction; Fig. 11 is a sectional plan view taken substantially on the line 11-11 of Fig. 1, illustrating particularly the jack supporting and controlling mechanisms; Fig. 12 is a view looking from the right, a portion 40 of the casing being broken away to illustrate substantially the parts shown in Fig. 11, together with the machine starting treadle and the toggle mechanism for tripping the jack into 45 operation; Fig. 13 is a view in right side elevation of the forward part of the head section of the machine, illustrating particularly the sewing mechanism, welt feeding and slashing devices, and the lasting grippers; Fig. 14 is a sectional 50 plan view taken substantially on the line 14-14 of Fig. 13, but with the sewing cam shaft and its associated cams removed; Fig. 15 is an enlarged detail view in right side elevation of the feed slide of the machine supporting the needle, awl and channel guide, the channel guide, however, having been removed in this figure; Fig. 16 is a sectional view in front elevation taken on the line 16-16 of Fig. 15, but with the needle advanced 60° from the position shown in Fig. 15; Fig. 17 is a detail sectional plan view taken on the line 17-17 of Fig. 15; Fig. 18 is an enlarged detail perspective view illustrating particularly the needle threading looper in relation to the needle and thread finger during the needle threading operation; Fig. 19 is a detail sectional view of the looper eye taken on the line 19-19 of Fig. 18; Fig. 20 is a detail sectional view taken on the line 20-20 of Fig. 18; Fig. 21 is a detail 55 sectional plan view of the welt feed finger and

its actuating mechanism taken on the line 21—21 of Fig. 13; Fig. 22 is a detail sectional plan view of the stop motion for the sewing cam shaft taken on the line 22—22 of Fig. 4; Fig. 23 is a somewhat fragmentary view in left side elevation of a portion of the sewing head illustrating particularly the welt guide, the welt cutter, the thread cutter and clamp, and the actuating mechanisms for these parts in the normal operating position with the needle at the limit of its loop drawing stroke; Fig. 24 is a fragmentary view of the mechanism for advancing the thread gripper and severing device, to illustrate the manner in which the latch for releasing the thread gripper is withdrawn at the beginning of the welt cutting and thread gripping and severing operations; Fig. 25 is a view similar to Fig. 23, but with the parts in the position taken during the stopping of the machine in which the welt knife has been partially advanced and the thread gripper has been located in position to grip the thread; Fig. 26 is a detail sectional view taken on the line 26—26 of Fig. 25; Fig. 27 is a fragmentary plan view illustrating the welt knife and the thread gripper in the position shown in Fig. 25; Fig. 28 is a detail plan view of the thread gripper and its supporting slide as shown in Figs. 25 and 27; Fig. 29 is a view similar to Fig. 28, but with the supporting slide or tube for the gripper fully advanced to close the gripper and sever the thread; Fig. 30 is an enlarged end view looking from the right showing the thread gripper jaw in the closed position of Fig. 29; Fig. 31 is a view similar to Figs. 23 and 25, but with the welt knife and the thread gripper and severing mechanism in its fully advanced position to sever the welt and to grip and sever the thread; Fig. 32 is a view similar to Fig. 31, but with the parts in their final stop position upon stopping the machine; and Figs. 33, 34, 35 and 36 are somewhat fragmentary detail views looking from the left of the machine, showing the main take-up lever, the stop arm, the thread tensioning brake, and the mechanism controlled through the operation of these parts and the lock bolt carrier, for releasing and engaging the thread tension, Fig. 33 showing the parts in the stop position of the machine with the tensioning brake latched in open position to release the thread tension, Fig. 34 showing the parts in the position taken as the take-up nears the completion of its first downward loop drawing stroke in the sewing of a new seam, and in which the tensioning brake is still held in its open position, Fig. 35 showing the parts in the position taken as the take-up nears the completion of its second downward loop drawing stroke in the sewing of a new seam, and in which the tensioning brake has just been tripped into second position, tension still off, and Fig. 36 tripped into position to put tension on.

The machine disclosed in the drawings is an automatic machine for sewing the welt and upper to the insole of a welt shoe, and comprises generally a sewing head having a curved hook needle arranged to enter the work from the sole side and a work perforating awl arranged at the opposite side of the work from the needle for sewing the insole of a welted shoe, a shoe supporting jack, pattern control mechanism for imparting turning, tipping and feeding movements to the jack and shoe supported thereon to transfer the point of operation about the margin of the shoe sole, together with mechanism operated in jacking the shoe to adjust the pattern mech-

anism in accordance with the size of shoe being operated upon, and driving and stopping mechanism arranged to operate automatically at the completion of the sewing operation to release and to move the jacked shoe away from the sewing mechanism, and to return the several operating mechanisms including the jack and the pattern devices associated therewith to a convenient starting position preparatory for the removal of the completed shoe and the jacking of a new shoe in the machine.

As best shown in Figs. 1, 2 and 3 of the drawings, the machine casing or frame is of the column type and is built up of several sections including a floor section 100 in which are mounted the various foot treadle controls, a middle section 102 housing principally the jack supporting mechanism and the pattern mechanism of the machine, a head section 104 housing therein the welt sewing mechanism and the driving and stopping mechanisms of the machine, and a top section 106 supporting thereon a driving motor 108 and reduction driving gears therefrom.

As in applicant's copending application above referred to, the drive is taken from the motor 108 directly downwardly to the sewing head casting 104 to the stop motion and to the sewing cam shaft, and thence downwardly to the pattern mechanism of the machine. This mechanism is illustrated in Figs. 1, 4, 5 and 6 of the drawings, and will be briefly described as follows; The armature shaft 110 of the motor is connected through reduction gears 112 and 114 to drive a vertically arranged driving shaft 116 which is in turn connected by means of gears 118 and 120 to drive an externally coned clutch member 122 forming the driving element of the main driving clutch. The clutch member 122 is supported against movement axially and is sleeved to a vertically arranged main drive shaft 124 to turn loosely thereon. These parts are driven continuously. The cooperating driven element of the main driving and stopping clutch comprises an internally coned clutch member 130 keyed to turn with and to slide on the drive shaft 124. A compression spring coiled about the drive shaft 124 tends normally to hold the driven clutch member 130 in a raised disengaged position with relation to the driving clutch member 122. The driven member 130 of the main starting and stopping clutch is arranged through its spline connection with the vertical drive shaft 124 to drive the pattern mechanism of the machine including the pattern cam shaft. The driven clutch member is also connected to drive the sewing cam shaft 132 through the meshing engagement of a spiral gear 134 formed on the outer periphery of the driven clutch member 130 with a spiral gear 136 secured to the sewing cam shaft 132. With this construction and arrangement of the driving mechanism, it will readily be seen that the disengagement of the main driving clutch will operate to disconnect the drive to each of the sewing head and the pattern mechanism of the machine.

In stopping the machine, the sewing cam shaft is first brought to a gradual stop and then is driven through a predetermined distance in a reverse direction by means of slow speed reverse driving connections and a friction clutch mechanism on the sewing cam shaft. The sewing cam shaft stopping and reversing clutch mechanism is arranged to be thrown into operation as the main clutch 130 is disengaged in stopping the

machine. The reverse driving connections referred to, as best shown in Figs. 4 and 22, comprise a forwardly extending reverse drive shaft 140 which is continuously driven from the gear 118 through the engagement therewith of a worm gear 142 on the shaft 140. Adjacent its forward end the reverse drive shaft 140 carries a worm 144 which meshes with a worm gear 146 loosely sleeved on the sewing cam shaft 132. The gear 146 has formed integrally therewith an internal cone-shaped friction clutch surface 148, and forms the driving element of the sewing cam shaft reversing and stopping clutch. The co-operating driven member of this clutch designated at 150 is provided with a cooperating external coned clutch surface, and is keyed to turn with and to slide axially on the sewing cam shaft 132. A compression spring 152 coiled about the sewing cam shaft 132 and arranged to gear at one end against the sleeve hub of the driven clutch member 150 and at its other end against a disk 154 secured to the cam shaft, tends normally to maintain the clutch in open position.

The mechanism for operating the sewing cam shaft reversing and stopping clutch, as best shown in Figs. 4, 5 and 22, comprises a bell-crank clutch shifting lever 156 which is supported on a vertical pivot 158, and carries on one arm thereof a roller 160 engaging in a cam track 162 in the sleeve hub of the shiftable clutch member 150. During normal operation in which the clutch is disengaged, the bell-crank lever 156 has an idling motion determined by the contours of the cam track 162. As the same time that the main clutch 130 is disengaged in stopping the machine, a vertically arranged lock bolt 164 carried in the rearwardly extending end of a lock bolt carrier or slide 166, is permitted to engage within a socket formed in the free end of the bell-crank 156. The slide 166 is supported in a casing 168, and is acted upon by a compression spring 170 coiled about a reduced portion of the slide which tends to maintain the same in a fully extended rearward position. During continued rotation of the sewing cam shaft and clutch member 150, the position of the bell-crank shifting lever 156 is controlled by its connection with the lock bolt 164 and lock bolt carrier 166 so that the roller 160 riding in the cam track 162 acts to engage the clutch member 150 with the reverse driving clutch member 148 acting to frictionally stop and thereafter to drive the sewing cam shaft 132 in a reverse direction, to a predetermined angular stop position in which the clutch member 150 is again moved to inoperative position. During this operation of stopping and reversing the sewing cam shaft, the clutch control bell-crank lever 156 and slide 166 will be moved forwardly against the pressure of spring 170 and then rearwardly to the final stop position shown, for example, in Figs. 4 and 22.

In order to stop the sewing cam shaft 132 in its predetermined stop position, a stop arm 167 is provided (see Fig. 5) which is loosely supported at its upper end on a transversely extending pivot shaft 169 located substantially above the sewing cam shaft, and at its lower end is provided with a roller 171 for engagement with a cam disk 173 on the sewing cam shaft 132. During the normal rotational movement of the sewing cam shaft in a clockwise direction as viewed from the right side of the machine, the roller 171 is held out of engage-

ment with the cam disk 173. However, during the reverse movement of the sewing cam shaft in stopping the machine, the roller 171 is arranged to engage with and ride inwardly in a stop cam groove 175, so that as the roller 171 reaches the bottom of the groove 175, the cam shaft is brought to a positive stop.

The mechanism for controlling the operation of the main stopping and starting clutch 130 of the machine, and for shifting the lock bolt 164 into and out of operating position to control the operation of the sewing cam shaft reversing and stopping clutch 150, as best shown in Figs. 1, 4 and 5, comprises a rock shaft 172 extending transversely of the machine and provided at its right hand end with a forked lever arm 174 which straddles a vertically extending treadle rod 176 and engages beneath a compression spring 178 coiled about the treadle rod 176. The spring 178 is seated at its upper end against a collar 180 fixed to the treadle rod 176. A forked clutch control lever 182 rigidly secured to the rock shaft 172 is arranged to bear against a thrust bearing 184 seated against the upper end of the sleeve hub of the main starting and stopping clutch member 130, and is rendered operative by a downward movement of the treadle rod to engage the main clutch. For controlling the operation of the lock bolt 164, there is also secured to the rock shaft 172, a downwardly and rearwardly extending lever arm 186 which carries a roller 188 adapted for engagement against a cam surface formed on a lever arm 190 secured to a rock shaft 192 parallel to and beneath the rock shaft 172. At its left hand end the rock shaft 192 carries a lever arm 194 which is connected by a link 196 with the lower end of the lock bolt 164. The lock bolt 164 is forced yieldingly upwardly by a compression spring 198 coiled about a reduced portion of the lock bolt and seated at its lower end within the slide 166. There is also provided a tension spring 200 connected at one end to a pin 202 on the lever arm 186 and at its other end to a stationary pin 204 which tends to move the lever arm 190 out of engagement with the roller 188 and to permit movement of the lock bolt 164 upwardly into operating position. During normal operation of the machine in which the treadle rod 176 is in its depressed position, and in which the rock shaft 172 has been rocked in a clockwise direction, the lever arm 186 will occupy a relatively depressed position in which the roller 188 bearing against the cam surface of the lever 190 supports the lock bolt in a depressed inoperative position. When the treadle rod is released and permitted to move upwardly in stopping the machine, the corresponding upward movement of the lever arm 186 and roller 188 permits the lever arm 190 to move rearwardly under the influence of spring 198 to raise the lock bolt into position in which it will engage within the recess formed in the free arm of the clutch controlled bell-crank lever 156 to engage the sewing cam shaft reversing and stopping clutch 150.

The pattern cam shaft of the machine generally designated at 210 is driven from the main starting and stopping clutch through connections which include the clutch member 130 and vertical driving shaft 124, a secondary clutch, a variable speed mechanism and a reduction gear train which may be of ordinary description. As best shown in Figs. 5, 6 and 7, the drive shaft 124 is connected at its lower end through a ratchet toothed clutch to drive a stub shaft 212

in axial alignment therewith. The secondary clutch referred to, comprises a driving clutch element 214 keyed to turn with and to slide axially upon the drive shaft 117 for engagement with a cooperating clutch member 216 fast on the shaft 212 to which is secured a driving ratchet 218 forming part of the variable speed driving mechanism for the pattern cam shaft 210. The ratchet is arranged to be engaged by four pawls 220 on three-cornered levers 222 pivotally supported on a circular plate 224 forming part of a sleeve member 226 which is loosely mounted to turn on the shaft 212, and comprises the driven element of the variable speed mechanism. The sleeve member 226 is externally supported in a bushing 228 carried in a bearing formed in the top surface of the middle section 102 of the machine casing. Each of the three-cornered levers 222 is provided with an upwardly extending roller pin 230 engaging within a circular cam track 232 formed in the underside of an adjustable eccentric ring member 234 carried on a lever 235. The rate of rotation of the driven sleeve member 222 with relation to the drive shaft 117 and stub shaft 212 is determined by the eccentric adjustment of the ring 234. For effecting this adjustment there is provided on the side of the ring 234 opposite the pivot 236, a gear segment 238 which meshes with a gear segment 240 formed in a short lever arm 242 rigidly secured to a vertical rock shaft 244. The angular position of the rock shaft 244 is determined in accordance with the size of shoe being operated upon through the machine sizing device connected with the jack feed lever, as hereinafter more fully set forth.

As best shown in Fig. 6 of the drawings, the drive is taken from the sleeve member 226 to the pattern cam shaft 210 through a series of reduction gears including a gear 246 formed on the lower end of the sleeve 226, a gear 248 meshing therewith carried on a stub shaft 250, and thence through a gear 252 on the stub shaft 250 which meshes with a gear 254 on a vertical drive shaft 256. Also mounted on the shaft 256 are a number of driving gears 258 which mesh with a gear 260 on the pattern shaft 210 in any of its vertically adjusted positions.

The drive for the one revolution eccentric which is employed in stopping the machine to perform a number of auxiliary operations, and the reverse drive for the pattern cam shaft 210 are taken from the lower end of the vertical drive shaft 117 through a planetary gear train and a clutch device having neutral position and alternative engaging positions for driving the eccentric and the reverse driving connections for the pattern cam shaft. As best shown in Figs. 5, 6 and 7, the drive shaft 117 is provided adjacent its lower end with a spur driving gear 264 which engages with three planetary gears 266 carried on a spider 268 loosely sleeved to turn on the lower end of the drive shaft 117. Each of these gears also engages an internal stationary gear 270, so that the spider is caused to rotate with but at a slower rate than the drive shaft 117. Each of the gears 266 is integrally formed with a second gear 272 of smaller diameter which meshes with an internal gear 274 carried on the upper end of a short clutch supporting shaft 276 which is located directly beneath and in axial alignment with the drive shaft 117. The shaft 276 is continuously driven through the planetary mechanism above described. An eccentric cam 278 fitted with an eccentric strap 279 is loosely

sleeved to turn on a bushing support 280 for the shaft 276, and is provided with ratchet-shaped clutch teeth 282 for engagement with an eccentric and reverse driving clutch member 284 which is keyed to turn with and slide axially upon the shaft 276. Upward movement of the eccentric clutch member 284 to engaging position with teeth 282 causes the eccentric 278 to be driven from the drive shaft 117.

10 The clutch shifting mechanism, as shown in Fig. 5, comprises a forked clutch shifting lever 290 formed on a sleeve member 292 loosely mounted to turn on a control rock shaft 294, and having supported thereon tapered rollers 296 which engage in an annular groove 298 in the eccentric clutch member 284. For shifting the pattern cam shaft auxiliary clutch member 214, there is provided a forked clutch shifting lever 300 which has mounted thereon rollers 304 which engage in an annular groove 306 in the clutch member 214. The position of the clutch shifting lever 300 and pattern cam shaft auxiliary clutch 214 is determined in accordance with the position of the eccentric clutch shifting lever 290 by means of an actuating connection from the sleeve member 292, which comprises a forwardly extending lever arm 308 formed on the clutch sleeve 292, and provided at its forward end with a laterally extending roller 310 which engages in a V-shaped notch 312 formed in a downward extension of the auxiliary clutch shifting lever 300.

15 The control rock shaft 294 is operatively connected to the clutch sleeve 292 and clutch shifting levers actuated thereby, by means of a pin and slot connection which comprises a stop pin 314 secured to the rock shaft 294 and projecting through a transverse slot 316 in the sleeve member 292. Rocking movement of the sleeve 292 in a clockwise direction with respect to the shaft 294 as shown, for example, in Fig. 5, is limited by engagement of the stop pin 314 with one end of the slot. The limit of rotation of the sleeve 292 in a counterclockwise direction 20 with relation to the control rock shaft 294 is determined by the engagement of an adjustable stop pin 318 supported in an upwardly extending gear 320 on the sleeve member 292 with the stop pin 314. Under conditions of normal operation of the machine, the angular position of the control rock shaft 294 will be that illustrated in Fig. 5, in which the stop pin 314 is vertically located.

25 The sleeve member 292 weighted by the connected parts including clutch shifting lever 290, clutch member 284 and lever arm 308 is held yieldingly in the limiting position determined by the engagement of the stop screw 318 with stop pin 314 on the control rock shaft 294. A tension spring 303 tends to rock the shifting lever 300 to the right as shown in Fig. 1, and thereby to maintain the V-shaped notch 312 in operative engagement with the roller 310. For the rest position of the machine, as shown in Fig. 5, and also while the machine is in operation, the clutch sleeve 292, the eccentric clutch lever 290 and the auxiliary pattern shifting clutch control 308 will occupy an intermediate position determined by the engagement of the roller 310 in the bottom of the V-shaped slot 312, permitting the secondary clutch shifting lever 300 to be in its fully depressed position, and with the secondary clutch engaged.

30 In stopping the machine, the clutch sleeve 292 is arranged to be rotated in a clockwise direction

(Fig. 5), causing the eccentric clutch member 284 to engage with and positively drive the eccentric 278 through one revolution. This rotational movement of the sleeve 292 raises the lever arm 308 and roller 310 which rides outwardly on the upper side of the V-shaped notch 312, forcing the clutch shifting lever 300 upwardly to disengage the secondary pattern cam shaft clutch 214. The mechanism through which the engagement of the eccentric clutch 284 and the disengagement of the secondary pattern cam shaft clutch 214 is effected, comprises a rearwardly extending arm 326 which is formed on the left hand end of the sleeve member 292, and supports a notched detent member 328 for engagement with a corresponding notch 330 in a vertically movable eccentric clutch control rod 332. At its upper end the control rod 332 is pivotally connected to one arm of a bell-crank 334, the other arm of which is connected by a link 336 with the lock bolt carrier 166. In stopping the machine the lock bolt carrier, as above pointed out, is moved forwardly and then rearwardly, imparting to the control rod 332, a corresponding upward and downward movement which is operative to engage the notch 330 with the detent 328, and thereafter to depress the detent 328 and lever arm 326 to engage the eccentric clutch. At the end of one revolution of the eccentric 278, the lower end of the control rod 332 is moved rearwardly to release the detent 328, as hereinafter more fully described, permitting the clutch mechanism to again return to the position shown in Fig. 5, determined by the engagement of roller 310 in the bottom of the V-shaped slot 312 in which the eccentric clutch is in an intermediate neutral position, and the secondary pattern cam shaft clutch 214 is engaged.

The starting of the machine, as previously pointed out, is effected by a downward movement of the treadle rod 176 which rocks the shaft 172 to engage the main clutch 130 and to withdraw the lock bolt 164. This movement is effected through actuating connections including a foot treadle 352 carried on the forward end of a treadle lever 354 in the machine base (see Figs. 1, 11 and 12). The treadle lever 354 is secured at its rear end to a transversely extending rock shaft 356 which also carries a forwardly extending lever arm 358 to which is pivoted the lower end of a vertically extending connecting rod 360. At its upper end the connecting rod 360 is pivotally secured to a laterally extending lever arm 362 (Fig. 11) having the outer end thereof journalled to receive the lower end of the treadle rod 176. A collared nut 364 at the lower end of the treadle rod 176 is arranged to bear against the under side of the lever arm 362, so that downward movement of the lever 362 with the foot treadle 352 will act to depress the treadle rod 176. The treadle rod is then held in its depressed operating position by the engagement of the forward end of a latch bar 366 with a notch 368 in the treadle rod 176 (see Fig. 7).

The machine is stopped automatically upon the completion of the sewing operation about the margin of the shoe sole, by means of mechanism forming part of the stop motion of the machine which acts to withdraw the latch bar 366 from engagement with the notch 368 in the treadle rod 176, and thereby permits the opening of the main clutch 130 and the release of the lock bolt 164 for operatively connecting the sewing cam shaft clutch shifting lever 156 with the lock bolt carrier 166. As best shown in Figs. 7, 8, 9 and 10, 75

the latch bar 366 is pivotally connected at its rear end with a treadle rod release lever 370 which extends laterally of the machine, and is loosely mounted to turn on a vertically extending pivot shaft 372. A tension spring 374 connected at one end to a pin 376 on the treadle rod release lever 370 and at its other end to a point on the machine frame, tends to move the lever 370 in a direction to engage the latch bar 366 with the notch 368 in the treadle rod 176.

The mechanism for automatically throwing the stop motion into operation is actuated directly from the pattern cam shaft 210 after it has made nearly a complete revolution. To secure this result, a block 378 (see Figs. 7 to 10 incl.) is secured to the upper surface of the gear 260 at the upper end of the pattern cam shaft, which block after the pattern cam shaft has made nearly a complete revolution, engages with a wide-faced pawl 382 pivoted to a laterally extending arm 384 of a vertically disposed eccentric rock shaft 386, and moves said pawl outwardly from the gear 260 against the pressure of a tension spring 388 connected between the pawl 382 and a horizontally disposed plate 390 forming part of the machine frame. A roller 390 mounted on the upper edge of the pawl 382 is arranged for engagement with the edge of the fixed plate 390 to limit the movement of the pawl toward the gear 260 under the influence of spring 388. The outward movement of the pawl causes a cam surface 392 formed on a fixed projection 394 of the pawl 382 to engage with a cam roll 396 on the treadle release lever 370, moving the treadle release lever positively in a counterclockwise direction to withdraw the latch bar 366 from engagement with the treadle rod 176. The main clutch 130 is now permitted to open, and the lock bolt 164 is released, operatively connecting the sewing cam shaft shifting lever 156 with the lock bolt carrier 166. As previously pointed out, the subsequent forward and back motion imparted to the lock bolt carrier 166 is employed to impart an upward and downward movement to the eccentric clutch control rod 332 (see Figs. 5 and 7) to engage the eccentric clutch 284 with the eccentric 278 which is now driven through one revolution to impart a clockwise followed by a counterclockwise rocking movement to the eccentric rock shaft 386. In order to effect this movement, the eccentric strap 279 (see Fig. 7) is provided with a lateral extension which is pivotally connected to a lever arm 398 secured to the upper end of the eccentric rock shaft 386.

In order that the vertical reciprocating movement of the eccentric clutch control rod 332 may be rendered operative to engage the clutch, and also to provide means for subsequently disconnecting the eccentric drive after one revolution of the eccentric 278, the eccentric clutch control rod 332 is connected at its lower end to be swung forwardly and rearwardly about its pivotal connection with the bell-crank lever 334. As best shown in Figs. 5 and 7, the lower end of the eccentric control rod 332 is slidably engaged between two vertically extending pins 400 on a laterally extending eccentric control lever 402. The lever 402 is supported to turn on the fixed pivot 372 directly above the treadle release lever 370, and is connected to have only a limited movement with relation thereto. To this end the eccentric control lever 402 has formed on the opposite sides of the hub portion thereof, shouldered portions 406 and 408, the shouldered portion 408 being engaged by a spring-pressed

plunger 410 carried in a block 412 secured to the upper side of the treadle release lever 370 which serves to maintain the shouldered portion 406 in yielding engagement with an abutting shoulder 414 on the block 412. During the rocking movement of the treadle release lever 370 to its release position, the associated eccentric control lever 402 is biased also in a forward direction by the action of the spring-pressed plunger 410, so that during the subsequent upward movement of the eccentric control rod 382, this rod will be swung forward to engage the notch 380 with the notched portion 328 of the rearwardly extending arm 326 forming part of the eccentric clutch shifting lever.

With the present construction, connections are provided which are rendered operative by the rocking movements imparted to the eccentric rock shaft 386 to shift the eccentric control lever 402 rearwardly against the pressure of the plunger 410, and thereby to disengage the eccentric clutch 284 at the completion of one full revolution of the eccentric. The connections for effecting the disengagement of the eccentric drive comprise a short lever arm 416 on the eccentric rock shaft 386 which during the clockwise rotational movement of the eccentric rock shaft engages with but passes a yieldingly supported detent 418 on the eccentric control lever 402 (see dotted line position Fig. 10), and thereafter on its return movement in a counterclockwise direction as the eccentric completes one full revolution (see Figs. 9 and 10), positively engages the detent, thereby shifting the eccentric control lever 402 rearwardly, thus disengaging the eccentric control rod from the clutch shifting lever, and permitting the eccentric clutch 284 to return to its intermediate neutral position.

The rocking movement of the eccentric rock shaft 386 has for one of its functions to complete the rotation of the pattern cam shaft. During the clockwise movement of the eccentric rock shaft 386, the pawl 382 is withdrawn to a position in which the pawl rides off of the rear end of the block 378, and the fixed projection 394 is positioned behind the same, as shown in dot-and-dash lines in Fig. 10. During the subsequent counterclockwise rotation of the eccentric rock shaft, the pawl 382 is rendered operative to continue the rotation of the pattern cam shaft to its initial starting position.

The present invention is provided with a shoe supporting jack which may be of well known construction as that, for example, illustrated in the patent to Cross, No. 2,056,714, dated October 6, 1936. The jack comprises a toe supporting arm 420 rigid with a spindle 422 and a heel supporting arm 424 pivoted at its lower end on the upper end of the spindle 422. With the present construction, the jack is mounted on a supporting structure which, as best shown in Figs. 1, 11 and 12, comprises a horizontal supporting arm 426 in the forward end of which the lower end of the jack spindle is mounted to rotate and to swing freely on gimbal joints, a pitch support lever 428 on which the arm 426 is mounted to swing vertically, and a roll support lever or frame 430 pivotally mounted at its lower end in the machine base so as to be capable of swinging about a horizontal axis, and upon which the support 428 is mounted so as to swing about a substantially vertical axis. These parts are so arranged as to permit free rotational movement of the jack and its supporting spindle 422 on its gimbal joint, and for imparting forward and back or roll tip-

ping movements, and longitudinal or pitch tipping movements to the jack over a wide range of angles adaptable to the most extreme lasts, to properly position the shoe with relation to the sewing instrumentalities as the point of operation is transferred about the shoe.

Feeding movements are imparted to the shoe by means of a feed lever 432 located on the left side of the machine outside of the machine casing, and pivotally supported at its rear end for lateral swinging movements on a cross pin 434 on a laterally extending rock shaft 436 journalled in a bearing 438 at the rear of the machine. At its forward end the feed lever 432 is connected by means of a curved link 440 with the toe support 420 of the jack.

The pattern mechanism by means of which the various positioning movements are imparted to the jack, comprises the pattern cam shaft 210 which in the present machine is mounted rearwardly of the jack supporting structure in the central rear portion of the machine casing, see Figs. 11 and 12, and has supported thereon in accordance with the usual practice, a bank of pattern cams comprising five alternatively available sets of operating cams. The cam actuated levers cooperating with the cams are in the present construction supported on a vertical pivot shaft 442 located at the left side of the pattern cam shaft 210, each of the cam levers being arranged to extend laterally and with their cam engaging rollers in contact with the front side of the associated cams.

Longitudinal pitch tipping movements are imparted to the jack by means of a pitch cam lever 444 supported adjacent the lower end of the pivot shaft 442 and having intermediate its length an offset portion forked to receive a cam roller 446 for engagement with a cooperating pitch cam 448 on the pattern cam shaft. The pitch cam lever is connected by a forwardly extending link 450 to a lateral extension of the support 428, the connection between the link 450 and the support 428 being located substantially on the line of centers of the pivot bearings 452, 454 of the frame 430.

Forward and back or roll tipping movements are imparted to the jack by means of a roll cam lever 456 supported on the pivot shaft 442 above the pitch cam lever 444, and having a roller 458 which engages with a cooperating roll cam 460 on the pattern cam shaft 210. The roll cam lever 456 is connected by a link 462 to an intermediate portion of the frame 430, this connection being located substantially on a vertical line of centers of the bearings 464, 466 for the support 428 in the frame 430. The roll support lever 430 takes the form roughly of an L within which the pitch support lever 428 is mounted to turn.

The mechanism for imparting turning movements to the jack comprises a turn cam lever 468 supported on the pivot shaft 442 above the roll cam lever 456, and provided with a roller 470 arranged to engage with a cooperating turn cam 472. A forward extension of the turn cam lever 468 has formed thereon a gear segment 474 which meshes with a pinion 476 (see Figs. 11 and 12) carried on the upper end of a cone-shaped pulley member 478. The member 478 is supported to turn on bearing pins 480, 482. Rotational movement is imparted to the jack from the pulley member 478 by means of a cord 484 which is secured at one end to a pulley 486 formed on the lower end of the member 478, and thence passes around an idler pulley 488 on the frame 430, an

idler pulley 490 on the support 428, an idler pulley 492 on the jack supporting arm 426, and around a wheel 494 supported to turn with the jack spindle 422. Thence the cord extends rearwardly over an idler pulley 496 and downwardly to a weight 498, which serves to maintain an adequate tension on the cord. It will be noted that the several idler pulleys are so arranged that the cord is carried through the line of centers of each of the bearing supports for each of the frame 430, support 428 and jack supporting arm 426, so that the tension on the cord will have no tendency to disturb or affect the operation of these parts as controlled by their cooperating pattern cams. From an inspection of Fig. 11, it will be noted that the two legs of the cord 484 extending rearwardly from the wheel 494 by which the jack is rotated, extend rearwardly toward the right side of the machine, so that the tension on the cord has a tendency to swing the supporting arm 426 and the base of the jack to the right, and thereby to maintain the pitch cam lever 444 in engagement with its cooperating cam 448.

As best shown in Figs 2, 6 and 7, the feed lever 432 is connected intermediate its length by means of links 500 and 502 to the forward extension of a feed cam lever 504 supported on the pivot shaft 442 disposed from the pattern cam shaft toward the left side of the machine with the feed lever, and is provided with a roller 506 engaging with a cooperating feed cam 508 on the pattern cam shaft 210. The links 500 and 502 are arranged at an acute angle with relation to one another, being pivotally connected together by a pivot pin 509 and to the free end of a double link 510 which serves as a guiding link for the pivotal connection 509 of the links 500, 502. The link 510 is fulcrumed at 511 on a fulcrum carrying frame lever 512 which is mounted to turn on ball bearings 521 and 524 (see Fig. 6). Motion is transmitted from the feed cam lever 504 through links 500, 502 to the feed lever 432, the extent of this motion being determined in accordance with the direction of movement imparted to the pivotal connection 509 by the guiding link 510.

To adapt the machine for operation upon shoes of different sizes, the frame lever 512 is adjustable about its pivot to change the position of the fulcrum 511 of the guiding link 510. The fulcrum carrying frame lever 512 is held in locked and adjusted position during the operation on the shoe by mechanism comprising a laterally extending rod 516 connected at one end by means of a connecting pin 517 to the fulcrum carrying frame lever 512, and at its other end arranged to be engaged by a locking device indicated in dotted lines at 518 in Fig. 7. During the operation on the shoe, the locking device is operative to support the fulcrum carrying frame lever 512 in locked position. The placing of a new shoe on the jack acts to release the locking device 518, so that the fulcrum carrying frame lever 512 is unlocked and adjustment of the mechanism for actuating the feed lever can be made by movement of the jack to starting position. The fulcrum carrying frame lever is locked in position on starting the machine through connections controlled from the starting treadle.

The position of the fulcrum carrying frame lever 512 is employed also to effect an adjustment of the variable speed pattern shaft driving mechanism in accordance with the size of the shoe being operated upon. Referring specifically to Figs. 6 and 7, it will be seen that there is secured to

the lower end of the variable speed control rock shaft 244, a lever arm 520 having at its outer end a slotted portion which engages the upper end of the connecting pin 517 on the fulcrum carrying frame lever 512, so that any pivotal adjustments of the fulcrum carrying frame lever 512 will effect a corresponding adjustment in the angular position of the variable speed rock shaft 244 and eccentric cam ring 234 controlled thereby.

- 10 A take-up device is provided for exerting a force on the fulcrum carrying frame lever 512 and on the feed connections generally, tending to move the fulcrum carrying frame lever 512 toward one limit of its adjustment, and to keep the feed cam lever 504 in engagement with its cam. 15 In the construction illustrated, this force is applied by means of a long coil torsion spring 522 (Figs 11 and 12) carried in the base portion of the machine on a transversely extending shaft 525 rotatably supported at one end in the bracket 526, and at its other end in a bearing 528 secured to the right side of the machine casing. The spring is connected at one end to a flanged drum element 524 pinned to the shaft 525. At 20 its other end the spring 522 is connected to a cross pin 530 on a pulley 532 loosely mounted to turn on the shaft 525. The pin 530 serves also as an anchor for one end of a metal strap 534 which passes upwardly around a pulley 536 on the 25 bell-crank lever 962, and then rearwardly around an idler pulley 538 carried on a lug 539 forming part of the casing for a snubber of ordinary description associated with the feed cam lever 504. Thence the strap 534 extends laterally around a 30 pulley 540 carried on a rearward extension 542 of the fulcrum carrying frame lever 512, and around a wheel 544 mounted concentrically with the ball bearing 514 for the lever 512, and then laterally to the feed lever 432 to which it is anchored.
- 35 40 The jacked shoe is forced yieldingly upwardly into operating position with relation to the shoe sewing mechanism during the operation about the shoe, and is then moved positively downwardly out of engagement therewith in stopping the machine, by mechanism which in the present construction comprises a vertically extending jack supporting rod 546 (see Figs 1, 2, 3, 11 and 12) connected at its upper end by means of a universal joint with the under side of the jack supporting arm 426, and at its lower end by means of another universal joint to the forwardly extending arm of a bell-crank lever 548 which is loosely supported to turn on the pivot shaft 356. A pair of heavy tension springs 550 connected at one end to the downwardly extending fork arms of the bell-crank 548 and at their other ends to the machine frame, tend to move the lever 548 and supporting rod 546 upwardly to maintain the jacked shoe yieldingly in engagement with the sewing mechanism.

45 50 55 Toggle mechanism is provided which is arranged to be moved to a straightened position in stopping the machine to move the bell-crank lever 548 and jack supporting rod 546 downwardly to move the jacked shoe out of engagement with the sewing devices. The eccentric drive above described, has for one of its functions in connection with the stopping of the machine to straighten this toggle and thereby to move the jacked shoe away from the sewing devices. As best shown in Figs. 1 and 12 of the drawings, the toggle mechanism comprises pivotally connected toggle arms 552 and 554, the toggle arm 552 being pivotally connected to the bell-crank lever 548, and the toggle arm 554 being secured to a

laterally extending rock shaft 556. Abutting stop surfaces formed on the rear side of the toggle arms 552 and 554 are arranged to support the toggle arms in their straightened locking position. A tension spring 560 connected at its forward end to the toggle arm 554 and at its rear end to a point on the bell-crank lever 548, tends to rock the toggle arms rearwardly to break the toggle. The tension of this spring is, however, insufficient to break the toggle until it has been moved from its locked position to a substantially straightened and overbalanced position. This mechanism including the toggle arms 552 and 554 and spring 560 are so arranged that a downward pressure or jiggling action on the jack applied by the operator when jacking a new shoe through its action to straighten the toggle, will serve to break the toggle and allow the shoe to be forced upwardly into position against the sewing mechanism by the springs 550 acting on the bell-crank lever 548.

The connections through which the eccentric drive is rendered operative in stopping the machine to straighten the toggle and thereby to move the jacked shoe downwardly away from the sewing mechanism, comprise a vertically extending toggle control rod 562 (see Fig. 1) which at its lower end passes through an aperture in a forwardly extending arm 564 formed integrally with the sleeve hub of the toggle link 554. A collar 566 supported on the lower end of the toggle control rod 562 by means of a pair of check nuts, is rendered operative by upward movement of the toggle control rod to engage with the under side of the arm 564, and to move the toggle to its straightened position. The toggle control rod, as best shown in Figs. 1, 3, and 6 to 10 inclusive, is connected to one arm of a bell-crank lever 568, the other arm of which is connected by a link 570 with a lever arm 572 on the eccentric rock shaft 386. The clockwise rotational movement of the eccentric rock shaft to the dot-and-dash position shown in Fig. 10, acts through this connection to move the toggle to its straightened and locked position. As the jack supporting arm 426 is moved downwardly by the straightening of the toggle 552, 554, the jack is permitted to fall outwardly away from the machine under the influence of a tension spring 574 connected between a downward extension 576 of the jack spindle 422 and the jack supporting rod 546. The extent of this outward movement of the jack is limited by a chain 578 connected between the jack spindle 422 and a stationary point on the arm 426.

The device for locking the feed connections and the variable speed drive for the pattern cam in their adjusted positions in accordance with the size of shoe being operated upon, is arranged to be locked by the downward movement of the foot treadle 352 in starting the machine, and to be again unlocked to permit the adjustment of this mechanism during the jacking of a new shoe by the breaking of the toggle 552, 554 in moving the newly jacked shoe to its operating position. The connections for locking and unlocking the locking device (see Figs. 3 and 7) comprise a vertically extending rod 580 connected at its upper end to a cross yoke 582 having pin and slot connections with two small locking levers 584 carried on the block 518 of the locking device. Downward movement of the rod 580 serves to bring the cammed hub portions of the locking levers 584 into locking engagement with the locking rod 516. At its lower end the rod 75 in the stitch receiving channel to form the so-

580 is connected to a laterally extending arm 586 (see Figs. 3, 11 and 12). A compression spring 588 inserted between a collar 590 on the lower end of the rod 580 and the under side of the lever arm 586 through which the rod 580 passes, provides a yielding connection through which a locking pressure is maintained on the locking levers 584. The lever arm 586 is arranged to be moved downwardly by the action of the starting foot treadle 352 to apply the locking device, and then to be latched in this position through connections which include a vertically extending lock control rod 592 connected at its upper end to the lever arm 586 and at its lower end connected with the treadle actuated lever arm 358. The rod 592 passes through an aperture in the lever 358, and is provided at its lower end with a collar 594 arranged to engage with the under side of the treadle actuated lever arm 358 (see Figs. 1 and 12). The control rod 592 when moved downwardly by the foot treadle, is retained in locking position by the engagement of a latch lever 596 above the offset lower end of a latch arm 598, and adjustably secured to the control rod 592. 25 The latch 596 is urged yieldingly toward latching position by a tension spring 600 connected at its rearward end to an upward extending arm of the latch lever 596, and at its forward end at a fixed point on the machine frame. A tension spring 602 connected at its lower end to the locking control rod 592 and at its upper end to a point on the machine frame, tends to move the locking control rod 592 upwardly when released from the latch 596 to disengage the feed connection locking device. 30 The breaking of the toggle 552, 554 operates to release the latch 596 to release the locking device 518, and thereby to permit re-adjustment of the feed connections and variable speed pattern shaft drive mechanism in accordance with the size of shoe being operated upon, through connections which comprise a spring-pressed trip plunger 604 carried in a rearwardly extending arm 608 secured to the rock shaft 556 for supporting the toggle member 554. The trip plunger 604 is arranged to cooperate with a forwardly extending trip arm 614 forming part of the latch lever 596. During the straightening movement of the toggle 552, 554, to the straightened position shown in Fig. 12, the trip plunger 604 snaps by the trip arm 614, passing over the cam surface thereof. The subsequent breaking movement of the toggle to the position shown in Fig. 1, and corresponding upward movement of the trip plunger 604, causes the plunger to positively engage the trip arm 614 to disengage the latch 596 so that the locking control rod 592 is permitted to move upwardly under the influence of its spring 602 to disengage the lock. 35 In accordance with the present invention, an inseam shoe sewing mechanism adapted for sewing a reverse chain is provided, of which the stitch forming and work guiding devices are particularly constructed and arranged to cooperate with the work supporting jack and the several automatic mechanisms of the machine for imparting positioning and feeding movements to the jack to transfer the point of operation about the sole margin of a shoe. The stitch forming and work guiding instrumentalities of the machine comprise a curved hook needle 620 arranged to enter the work from the sole side and to emerge through the upper and welt so that the chain loops of the successive stitches are laid

called reverse chain, a work perforating awl 622 arranged at the opposite side of the work from the needle, and arranged to project entirely through the work into the stitch receiving channel, a looper 624, a thread finger 626, a take-up lever 627, a channel guide 628 and a welt guide 630.

The present machine is also provided with a side lasting gripper mechanism including a gripper jaw 632 and a cooperating gripper jaw 634 pivoted thereto. However, inasmuch as the side lasting gripper together with its supporting and actuating mechanism forms specifically no part of the present invention, and is fully described and claimed in applicant's copending application above referred to, specific description of the construction and operation of the side lasting gripper in this machine is omitted.

The stitch forming mechanism including the needle, looper, thread finger and take-up operate in a manner which is in many respects similar to the sewing mechanism of applicant's prior Patent No. 2,041,945, to form the successive stitches of the seam. In the machine of the patent, however, these instrumentalities together with the work guiding and feeding mechanism including the channel guide and welt guide, are particularly constructed and arranged for imparting a continuous advancing movement to a shoe while held in the hand of the operator. In the machine of the patent, the rate of feed and the length of successive stitches is entirely controlled by the operation of the stitch forming and work feeding and guiding devices housed in the sewing head. With the present construction, a novel arrangement of the stitch forming and work feeding and guiding devices is provided which will adapt this mechanism for use in a fully automatic machine having a shoe supporting jack and mechanism for imparting positioning and feeding movements to the jack, and in which the feeding of the shoe is taken over by and is controlled by the pattern mechanism of the machine.

The present machine differs in important respects from automatic welt shoe sewing machines of the prior art, in which a curved hook needle is employed arranged to enter the work from the welt side and to emerge from the insole for the sewing of a conventional outside chainstitch. In such machines the needle has been employed to perforate the work, and the awl has been omitted in order to facilitate this positioning and feeding of the work by the jack during that portion of the stitch forming cycle when the needle is out of the work. In the reverse chain mechanism of the present construction, the use of a work piercing awl is required to prevent possible tearing of the loosely held upper and welt by the needle, and to insure the movement of the needle in its proper path through the work during the work piercing stroke.

In accordance with the present invention, an arrangement of the needle and awl is provided which will cause these elements to cooperate with the automatic jack positioning and feeding devices for feeding the shoe. Each needle and awl is arranged to be fed positively in the direction of feed while engaged in the work, and at a feeding rate which is substantially that imparted to the jacked shoe by the pattern mechanism. The work piercing and retracting movements of the needle and awl are timed with relation to one another to provide a substantial dwell

period which may approximate 60° of rotation of the sewing cam shaft between the moment at which the needle leaves the work and the moment at which the awl enters the work. During this period, the shoe is advanced solely by the pattern controlled jack positioning and feeding mechanism which now acts to correct any error in the rate of advance of the shoe which may have been introduced by the positive work feeding movements of the awl and needle.

Further in accordance with the invention, applicant provides a novel construction and arrangement of the stitch forming and guiding instrumentalities in which the needle, awl and channel guide of the machine are supported on a single feed slide, and are permanently aligned and supported with relation to one another to cooperate in a most efficient manner with the jack positioning and feeding mechanism to provide an adequate support for the shoe during the entire stitch forming cycle, and more particularly to cause the channel guide most effectively to support the shoe against the thrust of the awl during its work piercing stroke.

In the illustrated construction, the needle 620, awl 622 and channel guide 628 are mounted to move as a unit with the shoe in the line of feed, and to be back fed during the continued advance of the shoe by the jack after the needle is withdrawn from the work, and before the awl enters the work. With this construction, the needle and awl are mounted permanently in alignment with one another, and the channel guide 628 is mounted in fixed relation to the path of movement of these implements and closely adjacent thereto, so that a maximum support will be provided for the shoe against the work piercing thrust of the awl.

The needle, awl and channel guide are mounted on a feed slide 636 which, as best shown in Figs. 15 to 17 inclusive, is supported to slide on a horizontally arranged pin 638 rigidly secured in a journal formed in a stationary bracket 640 on the machine. To prevent angular movement of the feed slide 636 on the pivot 638, a downward extension of the feed slide engages within a slotted portion 642 of the bracket 640. The downward extension of the feed slide 636 provides support for a bearing pin 644 on which are carried a needle segment 646, an awl segment 648 and a needle guide 650. A flanged portion 652 of the awl segment 648 is arranged to ride in an arcuate track 654 formed in the upper portion of the slide 636 to provide additional lateral support for the awl. The channel guide 628 is formed on an L-shaped bracket 656 which is grooved to fit over a tongued block 658 formed on the outer end of the bearing pin 644, and is secured in a desired position of vertical adjustment thereon by means of a clamping screw 660.

Reciprocating movements are imparted to the feed slide 636 by means of a feed lever 662 supported intermediate its length on a vertical pivot post 664, and having the forward end arranged to engage within a slot 666 in the feed slide 636. The feed lever 662 is provided at its rear end with a vertically extending cam roll 668 for engagement in a peripheral groove of a feed cam on the cam shaft 132 of the machine (see Figs. 13, 14 and 16).

Oscillatory retracting and work piercing movements are imparted to the needle from a cam groove formed in a face cam on the cam shaft 132 through a series of levers and links comprising a cam actuated lever 670, a link 672, a swing-

ing arm 674 pivoted on a rock shaft 676 on the machine, and a link 678 connecting the swinging arm 674 with the needle segment 646. Oscillating, work piercing and retracting movements are imparted to the awl from a face cam groove in a cam on the cam shaft 132 through a series of levers and links similar to those for actuating the needle. These levers and links comprise a cam actuated lever 680, a link 682, a pivotally mounted arm 684 and a connecting link 686.

The looper 624 and thread finger 626 have substantially the same construction and arrangement of these parts, except as hereinafter pointed out, as the looper and thread finger of applicant's prior Patent No. 2,041,945 above referred to, the looper being arranged to swing across and outside the path of needle movement in an arcuate path, and the thread finger being arranged to move radially inwardly and toward the center of the needle circle and across the plane of the needle as shown in Fig. 18, to cooperate with the looper in placing the thread in the needle eye. As generally indicated in Fig. 13, and as more particularly shown in the patent above referred to, the looper through which the thread passes is formed on the forward end of a looper lever 688 which is pivotally mounted midway its length on the upper end of a bracket 690 forming a portion of the machine frame, and is provided at its rear end with a roll 692 engaged by a cam slot formed in the end of the downwardly extending arm of a cam-actuated lever 694. The cam slot is inclined to the path of movement of the lower end of the lever 688, and as the lever is oscillated, the looper is given a simple swinging movement to carry the eye of the looper back and forth across the plane of the needle.

The thread finger is secured at the forward end of a three-cornered support or plate 696. The support 696 is mounted to slide forwardly and backwardly and laterally on the bracket 690 by means of a guiding portion near its forward corner engaging a horizontal guiding slot in the bracket. At its two rear corners the support 696 is mounted by means of universal joints upon the lower ends of two cam-actuated levers 693 and 700 (see Fig. 14). These levers sustain the rear portion of the support 696, and by their relative movement impart the desired forward and back and lateral movements to the thread finger.

The take-up lever 627 as shown in Fig. 4, is supported to turn on a pivot 702, and is given a continuous oscillatory movement by means of a cam on the cam shaft 132. The take-up lever is arranged to act against a thread tension provided by a tension wheel 704 to draw in the previous stitch, and thereafter to draw off additional thread from the supply through the tension. Tension is supplied by means of a brake lever 706 and brake shoe 708 which engages with a friction drum secured to turn with the tension wheel 704 under variable pressure determined by a tension spring 710 connected between the brake lever 706 and take-up lever 627. As best shown in Fig. 4 of the drawings, the thread drawn from the supply passes around the tension wheel 704, and thence around an idler pulley 712, around a take-up pulley 714 on the take-up lever 627, and around an idler 716 carried on the looper lever 688, and thence to the looper.

In accordance with one feature of the invention, a novel and improved arrangement of the looper is provided for ease of threading of the looper together with a thread friction which

5 serves to friction and thereby to maintain under a slight tension that portion of the thread extending from the idler pulley 716 to the looper eye. As best shown in Figs. 18 and 19, applicant provides a looper having an open eye to facilitate the threading of the looper. On that portion of the looper lever 688 extending from the idler pulley 716 to the looper eye, there is provided a relatively broad flat surface 718 against which the thread is engaged under light friction by means of a spring 720 coiled about and secured to a flanged sleeve 715 on a supporting screw 717 on the looper lever 688. In order to permit adjustment of the applied tension, the sleeve 715 is loosely supported to turn on the screw 717, and is clamped in adjusted position by means of a check nut 719 (see Fig. 20). With this construction and arrangement of the looper and thread frictioning spring 720, the thread passing through the looper eye is always maintained under a sufficient friction to prevent the thread from being inadvertently cast out of the looper eye. This friction is also sufficient in the event of thread breakage between the looper eye and the work to prevent the thread from being drawn upwardly into the machine, with the consequent delay and difficulty attendant on re-threading.

30 In the present machine, mechanism is provided which is rendered operative in stopping the machine to release the thread tension and to maintain the thread tension released while the machine is stopped, and is then rendered operative to engage the tension in starting the machine, but only after the first two stitches are formed. For disengaging the thread tension, a 35 downwardly extending arm 721 is provided formed integrally with the arm 726, and arranged at its lower end to be engaged by an abutment 722 on the lock bolt carrier 166. The initial forward movement of the lock bolt carrier which is operatively connected to the cam shaft by the lever 156 causes the lever arm 721 to be rocked forwardly through its engagement with the abutment 722 on the lock bolt carrier to move the brake lever 706 and brake shoe 708 out of engagement with the brake drum. These parts are held in their open position as the lock bolt carrier again moves rearwardly by the engagement of a latch 724 with a forwardly extending arm 726 formed integrally with the arm 721. The latch 724 is supported on a pivot pin 728 on the machine frame, and is held yieldingly in operative position with relation to the arm 726 by a small spring 730.

40 In accordance with the present invention, the latch mechanism above described, is arranged to prevent the application of the thread tension during the formation of the entire first stitch and during the up-draw movement of the take-up lever in the formation of the second stitch. The maintenance of the tension in its off position during the formation of the first two stitches of the seam has been found to be of particular advantage to prevent the thread from being forced out of the thread holding device upon starting of the machine, with consequent failure or inaccuracy of the stitch forming devices to properly form the stitches at the beginning of the seam. As the machine starts outward, movement of the stop arm releases the brake lever which is then held in an intermediate but still open position by the engagement of the latch 724 with the arm 726. As will be evident from an inspection of Figs. 33, 34, 35 and 36 of the drawings, the latch is provided with two notches 732,

134, the operation of the mechanism in stopping the machine having been adequate to cause the arm 726 to engage with the upper notch 732 of the latch 724. In accordance with the invention, mechanism is provided which is actuated by the take-up lever 627 during the formation of the first stitch to cause the arm 726 to be disengaged from the notch 732 of the latch 724 and to be engaged in the notch 734. During the formation of the second stitch, the take-up lever 627 operates to entirely release the latch to permit the applying of the tension on the thread. The connections controlled from the take-up lever for effecting release of the latch 724 comprise a second latch 736 pivotally supported on the latch 724, and arranged for engagement with a notch 738 formed in the hub of the take-up lever 627. The downward movement of the take-up lever 627 during the formation of the first stitch causes the latch 736 to engage in the notch 738, and to draw the latch forwardly a sufficient distance to cause the arm 726 to drop out of engagement with the notch 732 and into engagement with the notch 734. As the take-up lever 627 nears the completion of the first downward loop drawing stroke, a stop screw 739 on the latch 736 engages an abutment on the hub of the take-up lever 627 to release the latch 736 from the notch 738 (Fig. 34), and cause the latch 724 to be biased rearwardly under the pressure of its spring 730 to maintain the notch 734 in engagement with the arm 726. This is the position of the parts shown in Fig. 35. As the take-up lever 627 during the formation of the second stitch again rises to tighten the previously formed stitch and to draw thread from the supply for the second stitch, the latch 736 is again brought into engaging position with the notch 738, so that during the second downward stroke of the take-up lever 627 at the completion of the second stitch, the latch 736 acts again to move the latch 724 to the right to free the arm 726 from the notch 734 of the latch 724, thereby releasing the brake lever 706 which now acts to tension the thread. As the arm 726 drops out of engagement with the latch 724, the latter is permitted to return to an extreme position to the left under the pressure of its spring 730, in which position a tail of the latch 736 engages a stop screw 742, thus causing the latch 736 to be moved to a raised inoperative position, this being the position of the parts shown in Fig. 36.

As best shown in Figs. 5, 13, 23, 25 and 31 of the drawings, the welt guide 630 is secured to the forward end of a supporting bar 746 which is carried adjacent its forward end on a link 748 pivoted at 750 on the machine frame. At its rear end the bar 746 is carried on a downwardly extending arm 752 of a cam-actuated lever 756 loosely sleeved on a rock shaft 754. During each sewing cycle, the welt guide bar 746 is slightly retracted to permit the feeding of the work, and is then permitted to move yieldingly forwardly against the work under the influence of a tension spring 758 connected at one end to the cam lever 756, and at its other end to a cam-actuated ratchet pawl lever 760 which is arranged for engagement with a ratchet 762 on the lever 756, and serves to lock the welt guide 630 in welt engaging position.

Further in accordance with the present invention, certain operations which include the severing and advancing of the welt and the associated operation of gripping and severing the thread, are controlled from the auxiliary mecha-

nism operative in stopping the machine upon the completion of a seam in order to provide a finished job of shoe sewing, and also to release the shoe from the sewing mechanism, and to permit the return of the jack to an initial starting position preparatory for the jacking of a new shoe thereon. For severing the welt, a welt knife 764 is secured to the forward end of a bar 768 slidably supported in a groove formed in the welt guide bar 746. The bar 768 carrying thereon the welt severing knife 764 is advanced to sever the welt in stopping the machine by connections controlled from the eccentric rock shaft 386. The slide 768 is provided adjacent its rear end with a rack which is engaged by a gear segment formed on a lever arm 770 pivotally supported on a bracket 772 on the welt guide bar 746. The lever 770 has also mounted thereon a roll 774 which engages within a cam groove 776 formed in an actuating lever 778 secured to the rock shaft 754. A lever arm 779 on the rock shaft 754 is connected by means of a link 780 with a laterally extending lever arm 782 on the eccentric shaft 386. The clockwise movement imparted to the eccentric shaft 386 during the operation of the single revolution eccentric in stopping the machine, acts to rock the shaft 754 and lever 779 in a clockwise direction from the position shown in Fig. 5, and through the engagement of the roll 774 with the cam groove 776, causes the lever 770 to be correspondingly rocked in a clockwise direction to actuate the welt knife 764 to sever the welt. Subsequent counterclockwise movement of the eccentric shaft 386 to its initial starting position, serves to again retract these parts to their inoperative position.

The mechanism for advancing the severed end of the welt as generally indicated in Figs. 13 and 21, comprises a welt advancing finger 784 which is carried on the forward end of a rod 786 slidably supported in bearings 788 in the machine frame. A pin 790 secured to the rod 786 for engagement with a slot 792 in one of the bearings 788 serves to key the rod against rotational movement. In order that the finger 784 may effectively engage with and follow the welt which is advanced through the welt guide in a direction slightly angled from the path of movement of the rod 786, the finger 784 is pivotally connected to swing laterally with relation to the bar 786, being normally held in a straightened position by the engagement of a spring-pressed plunger 794 in the forward end of the bar with a lateral extension 796 formed on the hub portion of the finger 784. The rod 786 and finger 784 are normally held in a retracted inoperative position by means of a compression spring 798 coiled about the rod 786 between one of the bearings 788 and a collar 800 secured to the rod.

The rod 786 and welt finger 784 are advanced subsequent to the severing of the welt to advance the severed end through the welt guide by connections which comprise a rotatable shaft 802, at its lower end provided with a spiral gear 804 which meshes with a spiral gear segment 806 rigidly secured to the rock shaft 754 rotatable with the eccentric actuated lever 778. At its upper end the rock shaft 802 has secured thereto a supporting block 806 to which is pivotally connected a pawl 808. The pawl 808 has formed thereon a stop surface 810 which engages with a corresponding abutment 812 on the block 786 to limit the movement of the pawl in one

direction. A leaf spring 814 held by the securing screw for the block tends to maintain the pawl in this limiting position. The pawl is arranged to cooperate with a recessed shoulder 816 in the bar 786. Rocking movement of the shaft 802 in a clockwise direction which is effected by the clockwise movement of the stop motion eccentric shaft through the connections above described, serves to rock the pawl. Subsequent movement of the shaft 802 and pawl in a counterclockwise direction during the return counterclockwise movement of the eccentric shaft 386, causes the pawl to engage the recessed shoulder 816 to advance the rod 786 and finger 784 to advance the severed end of the welt. As the pawl returns to its starting position, the engaging shoulder 812 of the supporting block 806 will act to force the pawl again out of engagement with the recess 816, permitting the rod 786 and finger 784 to return to their original inoperative position under the influence of the spring 798.

In accordance with the present invention, a thread gripping and cutting mechanism is provided which is particularly adapted for use with a reverse chain inseam sewing machine to grip and to sever the thread extending from the welt side of the work, and which cooperates in a novel manner with the mechanism above described for severing and for advancing the welt. A feature of the invention consists in the novel construction and arrangement of the automatic means for causing the thread gripping and cutting mechanism to be thrown into operation upon the stopping of the machine at the completion of the seam, and for further actuating this mechanism to release the gripped thread substantially at the completion of the first stitch in the sewing of a new seam. In the automatic machine herein disclosed, the thread gripping and severing mechanism is arranged to be thrown into operation by the one revolution eccentric 278, the forward and return movement of the welt knife being specifically employed for this purpose.

The thread gripper and severing device as shown in Figs. 22 to 31 inclusive, comprises a rod 820 provided at its forward end with spring gripper fingers 822 and carried in a surrounding sleeve support 824 which has formed on the under side thereof and at its forward end a thread cutter blade 826. The sleeve support 824 is arranged for sliding movement in a guideway formed in a depending lug 828 on the forward end of the welt guide bar 746, and at its rear end is pivotally connected to a depending lever arm 830 loosely mounted to turn on a pivot pin 832. The gripper rod 820 is provided at its rear end with an upwardly extending butt 834 which engages alternatively with either of two stop lugs 836 and 838 to limit the movement of the gripper fingers in each direction.

Upon stopping the machine, the sleeve support 824 is moved forwardly from the extreme rearward position of Fig. 23, and carries with it the gripper rod 820 and gripper fingers 822 in their open position, to the position shown in Figs. 25 and 27, in which the fingers 822 are located on opposite sides of the thread and in which the butt 834 is brought into engagement with the stop lug 836. Continued forward movement of the sleeve support 824 produces a relative movement of the sleeve support 824 and gripper rod 820 to close the grippers on the thread, and causes the knife edge 826 to pass under and beyond the ends of the gripper fingers 822 to sever

the gripped thread, as shown in Figs. 29 and 31. A subsequent rearward movement of the sleeve support 824 then takes place to retract the thread gripping and severing mechanism to an intermediate position, which is that shown in Fig. 32, in which the thread gripper and cutter are retracted from the work, and in which the thread end remains held by the gripper. In this position of the parts the butt 834 of the gripper rod 820 is engaged against the rearward stop lug 838. After the machine is started and substantially at the completion of the first stitch, the lever arm 830 and sleeve support 824 are again moved to their fully retracted position, producing a relative movement of the sleeve support 824 and gripper rod 820 to open the gripper and release the thread.

The advancing and retracting movement of the welt knife bar 768 and welt knife 764 to sever the welt, is employed to impart the above described thread gripping and cutting movements to the thread gripping and cutting mechanism above set forth. The actuating connections comprise an actuating lever 840 supported on the pivot pin 832 at one side of the lever arm 830, and provided at its lower end with a slot 833 which engages therein a lug 844 on the lever arm 830. The slot 833 is of considerably greater width than the lug 844 to provide a lost motion connection between the actuating lever 840 and lever arm 830. There is also provided at the lower end of the actuating lever 840, a laterally extending pin 846 which is arranged to be engaged by an upwardly extending lug 848 formed on the welt knife bar 768. A tension spring 850 connected at one end with the welt guide bar 746 and at its other end to the lever arm 830, tends to move the lever arm 830 and thread gripping and cutting mechanism connected thereto, towards its retracted position. With this arrangement of the parts, it will readily be seen that the forward movement of the welt knife will cause the lug 848 to engage against the pin 846 to swing the actuating lever 840 in a counterclockwise direction first to engage the rear side of the slot 833 with the lug 844, and thereafter to advance the lever arm 830 and sleeve support 824, first to grip and then to cut the thread as above described. As the welt knife is then withdrawn, the lever arm 830 and the sleeve support 824 will be retracted under the pressure of the spring 850 to the intermediate rest thread holding position shown in Fig. 32, in which the butt 834 is engaged with the rear lug 838.

When the machine is started, the lever arm 830 and sleeve support 824 are moved to the fully retracted position shown in Fig. 23, to release the gripped thread end substantially at the completion of the first stitch of the seam. The oscillatory movement of the needle cam lever 670 is employed for this purpose. The actuating connections comprise a latch lever 852 pivotally supported on the upper end of the lever arm 830 and arranged for engagement with a downwardly extending latch arm 854 formed on the hub of the needle cam lever 670. A tension spring 856 connected at one end to a tail of the latch lever 852 and at its other end to the actuating lever 840 tends to swing the latch in a counterclockwise direction into engagement with the latch arm 854. An abutment 858 on the hub of the latch lever 852 is arranged for engagement with a cooperating abutment 860 on the hub of the actuating lever 840 to limit movement of the latch lever 852 under the influence of spring 856. Dur-

ing normal operation of the machine in which the lever arm 830 is supported in its extreme rearward position, and in which the actuating lever 840 is located at the limit of its movement in a clockwise direction as shown in Fig. 23, the latch lever 852 is located in an extreme advanced position in which it is not engaged by the latch arm 854 during the oscillatory movement of the needle lever 670.

In stopping the machine, the sewing cam shaft is first brought to rest with the needle withdrawn from the work, and with the latch arm 854 of the needle cam lever 670 in the position shown in Fig. 23. The welt knife and the thread gripping and severing mechanism are then actuated by the pattern controlled eccentric mechanism to sever the welt and to grip and sever the thread. In this cycle of operations, the initial movement of the actuating lever 840 causes the abutment 860 thereon to engage with the abutment 858 on the latch lever 852 to rock the same against the pressure of the spring 856. During the subsequent forward and partial backward movement of the lever arm 830, the latch lever 852 is then brought to rest in the engaging position shown in full lines in Fig. 32 beneath the latch arm 854. When the machine is again started, the needle cam lever 670 moves first in a clockwise direction to pass the needle through the work, and then in a counterclockwise direction to withdraw the needle and to draw the first needle loop through the work. During this movement of the needle cam lever 670, the latch arm 854 is moved first leftwardly to the dot-and-dash position shown in Fig. 32, permitting the latch lever 852 to rise into latching position, and then to the right, acting through the latch lever 852 and actuating lever 840 to move the lever arm 830 and support 824 to their fully retracted positions as shown in Fig. 23. Since the butt 834 of the gripper rod 820 is at this time engaged against its rear stop lug 838, a relative movement of the gripper rod and support 824 is produced which is effective to open the gripper fingers 822 to release the thread.

It will be understood that the invention is not limited to the specific embodiment shown, and that various deviations may be made therefrom without departing from the spirit and scope of the appended claims.

What is claimed is:

1. In an automatic inseam chainstitch shoe sewing machine, the combination of stitch forming and work guiding devices including a curved hook needle arranged to enter the work from the sole side for laying the successively formed chain loops of the seam on the sole, means for actuating said devices in accordance with a stitch forming cycle in which the work is positively controlled by said devices during a portion of said cycle, and is released therefrom during another portion of said cycle a work supporting jack, and automatic means for imparting tipping, turning and feeding movements to the jack to present the shoe to the stitch forming and work guiding devices and to transfer the point of operation about the sole margin of the shoe said automatic means being further constructed and arranged to support the shoe with relation to said devices during said first-mentioned portion of the stitch forming cycle, and to control the length of feeding movement of the shoe in said other portion of the stitch forming cycle when the work is released from said devices.

2. In an automatic inseam chainstitch shoe

sewing machine, the combination of stitch forming and work guiding devices including a curved hook needle arranged to enter the work from the sole side for laying the successively formed chain loops of the seam on the sole, a work perforating awl, actuating means for the needle and awl arranged to cause both the needle and awl to be withdrawn from the work during a portion of each stitch forming cycle, a shoe supporting jack,

5 and automatic means for imparting tipping, turning and feeding movements to the jack to present the shoe to the stitch forming and work guiding devices and to transfer the point of operation about the sole margin of the shoe, said automatic means being further constructed and arranged to support the shoe with relation to the needle and awl while in the work, and to control the length of feeding movement of the shoe in that portion of the stitch forming cycle when the needle and awl are withdrawn from the work.

3. In an automatic inseam chainstitch shoe sewing machine, the combination of stitch forming and work guiding devices including a curved hook needle arranged to enter the work from the sole side for laying the successively formed chain loops of the seam on the sole, a work perforating awl arranged at the opposite side of the work from the needle, a channel guide, actuating means for the needle and awl arranged to cause both the needle and awl to be withdrawn from the work during a portion of each stitch forming cycle, a shoe supporting jack, and automatic means for imparting tipping, turning and feeding

25 movements to the jack to present the shoe to the stitch forming and work guiding devices and to transfer the point of operation about the sole margin of the shoe, said automatic means being further constructed and arranged to support the shoe with relation to the needle and awl while in the work, and to control the length of feeding movement of the shoe in that portion of the stitch forming cycle when the needle and awl are withdrawn from the work.

4. In an automatic inseam chainstitch shoe

45 sewing machine, the combination of stitch forming and work guiding devices including a curved hook needle arranged to enter the work from the sole side for laying the successively formed chain loops of the seam on the sole and arranged to move with the work in the line of feed while engaged therewith and to be back fed

50 while out of the work, a shoe supporting jack,

55 and automatic means for imparting positioning and continuous feeding movements to the jack to transfer the point of operation about the sole margin of the shoe, said automatic means being arranged to advance the shoe with the needle and to control the continued advance of the shoe during the back feed of the needle.

5. In an automatic inseam chainstitch shoe

60 sewing machine, the combination of stitch forming and work guiding devices including a curved hook needle arranged to enter the work from the sole side for laying the successively formed chain loops of the seam on the sole, a work perforating awl arranged at the opposite side of the work from the needle, actuating means for the

65 needle and awl arranged to cause both the needle and awl to be withdrawn from the work during a portion of each stitch forming cycle, means for moving each of the needle and awl with the work in the line of the feed while engaged therewith and to back feed each of the needle and awl while out of the work, a shoe supporting jack, and automatic means for imparting posi-

tioning and continuous feeding movements to the jack, said automatic means being arranged to move the shoe with each of the needle and awl while engaged with the work and to control the continued advance of the shoe while both needle and awl are out of the work.

6. In an automatic inseam chainstitch shoe sewing machine, the combination of stitch forming and work guiding devices including a curved hook needle arranged to enter the work from the sole side for laying the successively formed chain loops of the seam on the sole, a work perforating awl arranged at the opposite side of the work from the needle, actuating means for the needle and awl arranged to cause both the needle and awl to be withdrawn from the work during a portion of each stitch forming cycle after the needle has left the work and before the awl enters the work, means for moving each of the needle and awl with the work in the line of feed while engaged therewith and to back feed each of the needle and awl while out of the work, a shoe supporting jack, and automatic means for imparting positioning and continuous feeding movements to the jack, said automatic means being arranged to move the shoe with each of the needle and awl while engaged with the work and to control the continued advance of the shoe while both needle and awl are out of the work.

7. In an automatic inseam chainstitch shoe sewing machine, the combination of stitch forming and work guiding devices including a curved hook needle movable in the line of feed and arranged to enter the work from the sole side for laying the successively formed chain loops of the seam on the sole, a work perforating awl arranged at the opposite side of the work from the needle, a support on which the needle and awl are moved as a unit in the line of feed and on which both the needle and awl are back fed after the needle has left the work and before the awl enters the work, a shoe supporting jack, and automatic means for imparting positioning and continuous feeding movements to the jack to transfer the point of operation about the sole margin of the shoe, said automatic means being arranged to move the shoe with the needle and awl while engaged in the work and to control the continued advance of the shoe during the back feed of the needle and awl.

8. In an automatic inseam chainstitch shoe sewing machine, the combination of stitch forming and work guiding devices including a curved hook needle movable in the line of feed and arranged to enter the work from the sole side for laying the successively formed chain loops of the seam in a stitch receiving channel on the sole, a work perforating awl arranged at the opposite side of the work from the needle, a channel guide, a support on which the needle, awl and channel guide are supported to be moved as a unit in the line of feed and to be back fed while both the needle and awl are out of the work, a shoe supporting jack, and automatic means for imparting positioning and continuous feeding movements to the jack to transfer the point of operation about the sole margin of the shoe.

9. In an automatic inseam chainstitch shoe sewing machine, the combination of stitch forming and work guiding devices including a curved hook needle movable in the line of feed and arranged to enter the work from the sole side for laying the successively formed chain stitches

5 of the seam in a stitch receiving channel on the sole, a channel guide, a support on which the needle and channel guide are arranged to be moved as a unit in the line of feed and to be back fed while the needle is out of the work, a shoe supporting jack, and automatic means for imparting positioning and continuous feeding movements to the jack to transfer the point of operation about the sole margin of the shoe, said automatic means being arranged to move the shoe with the needle in the line of feed and to control the continued advance of the shoe during the back feeding movement of the needle.

10. In an automatic inseam chainstitch shoe sewing machine, the combination of stitch forming and work guiding devices including a curved hook needle arranged to enter the work from the sole side for laying the successively formed chain loops of the seam on the sole, a work perforating awl arranged at the opposite side of the work from the needle, actuating means for the needle and awl arranged to cause both the needle and awl to be withdrawn from the work during a portion of each stitch forming cycle after the needle has left the work and before the awl enters the work, a channel guide, actuating means for the needle, awl and channel guide for moving each of these parts in the line of feed including a slide on which the awl and channel guide are supported in fixed relation to one another in the line of feed to provide a maximum support for the work against the work piercing thrust of the awl, a shoe supporting jack, an automatic means for imparting positioning and continuous feeding movements to the jack to transfer the point of operation about the sole margin of the shoe, said automatic means being arranged to move the shoe with each of the needle and awl while engaged with the work, and to control the continuous advance of the shoe while both the needle and awl are out of the work.

11. In an inseam chainstitch shoe sewing machine, the combination of stitch forming and work guiding devices including a curved hook needle movable in the line of feed and arranged to enter the work from the sole side for laying the successively formed chain stitches of the seam in a stitch receiving channel on the sole, a work perforating awl arranged at the opposite side of the work from the needle, a channel guide, and a support on which the needle, awl and channel guide are supported to move in the line of feed and to be back fed while both the needle and awl are out of the work.

12. In an inseam chainstitch shoe sewing machine, the combination of stitch forming and work guiding devices including a curved hook needle movable in the line of feed and arranged to enter the work from the sole side for laying the successively formed chain stitches of the seam in a stitch receiving channel on the sole, a work perforating awl arranged at the opposite side of the work from the needle, a channel guide, a support on which the needle, awl and channel guide are supported to move in the line of feed and to be back fed while both the needle and awl are out of the work, and means for effecting the continued feed of the shoe during the back feed of the needle, awl and channel guide.

13. In an automatic inseam chainstitch shoe sewing machine, the combination of a shoe supporting jack, automatic means for imparting positioning and continuous feeding movements

to the jack to transfer the point of operation about the sole margin of a shoe, stitch forming and working guiding devices including a curved hook needle arranged to enter the work from the sole side for laying the successively formed chain loops of the seam on the sole, a needle threading device, a welt guide, welt severing mechanism arranged to sever the welt at that side of the needle with the welt guide, a thread gripping and cutting mechanism arranged to grip the thread extending from the work to the needle threading device and to sever the thread from the work, and means for actuating each of said welt severing and thread gripping and cutting mechanisms.

14. In an automatic inseam chainstitch shoe sewing machine, the combination of a shoe supporting jack, automatic means for imparting positioning and feeding movements to the jack to transfer the point of operation about the sole margin of a shoe, stitch forming and work guiding devices including a curved hook needle arranged to enter the work from the sole side for laying the successively formed chain loops of the seam on the sole, a needle threading device, a welt guide, welt severing mechanism arranged to sever the welt at that side of the needle with the welt guide, a thread holding and cutting mechanism arranged to grip the thread extending from the work to the needle threading device and to sever the thread from the work, a driving and stopping mechanism for the machine including mechanism controlled by said automatic means upon stopping the machine at the completion of a seam for actuating said welt severing and thread holding and cutting mechanisms, and means operable upon the starting of a new seam for actuating the thread holding mechanism to release the thread end substantially at the completion of the first stitch.

15. In an automatic machine, welt shoe sewing mechanism including a cam shaft and a hook needle actuated thereby, a shoe supporting jack, automatic means for imparting positioning and feeding movements to the jack to transfer the point of operation about the sole margin of a shoe, a driving and stopping mechanism for the machine including means for stopping the sewing cam shaft with the needle withdrawn from the work, and an auxiliary mechanism actuated by said automatic means at the completion of a seam for the performance of certain operations after the machine has stopped, a thread gripping and cutting mechanism arranged to grip and to sever the gripped thread from the work, and means controlled by said auxiliary mechanism for actuating said thread gripping and cutting mechanism to grip and to sever the gripped thread from the work.

16. In an automatic inseam chainstitch shoe sewing machine, the combination of a shoe supporting jack, automatic means for imparting positioning and feeding movements to the jack to transfer the point of operation about the sole margin of a shoe, stitch forming and work guiding mechanism including a sewing cam shaft, a curved hook needle arranged to enter the work from the sole side for laying the successively formed chain loops of the seam on the sole, a needle threading device, a driving and stopping mechanism for the machine including means to stop the cam shaft with the needle withdrawn from the work, and an auxiliary mechanism actuated by said automatic means at the completion of a seam for the performance of certain opera-

tions after the machine has stopped, thread gripping and cutting mechanism arranged to grip the thread extending from the work to the needle threading device and to sever the thread from the work, and means controlled from said auxiliary mechanism for actuating said thread gripping and cutting mechanism.

17. In an automatic inseam chain stitch shoe sewing machine, the combination of a shoe supporting jack, automatic means for imparting positioning and feeding movements to the jack to transfer the point of operation about the sole margin of a shoe, stitch forming and work guiding mechanism including a sewing cam shaft, a curved hook needle arranged to enter the work from the sole side for laying the successively formed chain loops of the seam on the sole, a needle threading device, a driving and stopping mechanism for the machine including means to stop said cam shaft with the needle withdrawn from the work, and a one revolution eccentric rendered operative by said automatic means for the performance of certain auxiliary operations after the machine has stopped, a thread gripping and cutting mechanism arranged to grip the thread extending from the work to the needle threading device and to sever the thread from the work, and connections from said eccentric for actuating said thread gripping and cutting mechanism to grip and to sever the thread from the work.

18. In an automatic inseam chainstitch shoe sewing machine, the combination of a shoe supporting jack, automatic means for imparting positioning and feeding movements to the jack to transfer the point of operation about the sole margin of a shoe, stitch forming and work guiding mechanism including a sewing cam shaft, a curved hook needle arranged to enter the work from the sole side for laying the successively formed chain loops of the seam on the sole, a needle threading device, a welt guide, a driving and stopping mechanism for the machine including means to stop the cam shaft with the needle withdrawn from the work, and an auxiliary mechanism actuated by said automatic means at the completion of a seam for the performance of certain operations after the machine has stopped, a welt severing mechanism, thread gripping and cutting mechanism arranged to grip the thread extending from the work to the needle threading device and to sever thread from the work, and connections from said auxiliary mechanism for actuating said welt severing mechanism and said thread gripping and cutting mechanism.

19. In an automatic inseam chainstitch shoe sewing machine, the combination of a shoe supporting jack, automatic means for imparting positioning and feeding movements to the jack to transfer the point of operation about the sole margin of a shoe, stitch forming and work guiding mechanism including a curved hook needle arranged to enter the work from the sole side for laying the successively formed chain loops of the seam on the sole, a needle threading device, a welt guide, a welt severing knife, a driving and stopping mechanism for the machine including means operable upon stopping the machine for imparting an advancing and retracting movement to the welt knife, thread gripping and severing mechanism comprising a support arranged for advancing and retracting movement, thread gripping and cutting devices on said support rendered operative by the advancing move-

ment of the support to grip and to sever the thread from the work, and by the retracting movement of the support to release the gripped thread, a connection operated by the advancing movement of the welt knife to advance said support, and means operable in starting the machine to retract said support and thereby to release the thread from the gripper device.

20. In an automatic inseam chainstitch shoe sewing machine, the combination of a shoe supporting jack, automatic means for imparting positioning and feeding movements to the jack to transfer the point of operation about the sole margin of a shoe, stitch forming and work guiding mechanism including a sewing cam shaft, a curved hook needle arranged to enter the work from the sole side for laying the successively formed chain loops of the seam on the sole, a needle actuating cam lever, a needle threading device, a welt guide, a welt severing knife, a driving and stopping mechanism for the machine including means operable upon stopping the machine for imparting an advancing and retracting movement to the welt knife, thread gripping and cutting mechanism comprising a support arranged for advancing and retracting movement, thread gripping and cutting devices on said support rendered operative by the advancing movement of the support to grip and to sever the thread from the work, and by a retracting movement of the support to release the gripped thread, a pivoted supporting arm for the support, an actuating lever having a lost motion connection with said supporting arm and arranged to be acted upon by the welt knife during its advancing movement to advance the support, a latch mounted on said supporting arm, and a cooperating latch arm on the needle cam lever, and abutting surfaces on the actuating lever and latch rendered operative by the movement of the actuating arm in advancing the support to position the latch beneath the latch arm whereby rocking movement of the cam lever upon starting the machine is effective to retract the support to release the thread from the gripper.

21. In an automatic inseam chainstitch shoe sewing machine, the combination of a shoe supporting jack, automatic means for imparting positioning and continuous feeding movements to the jack to transfer the point of operation about the sole margin of a shoe, stitch forming and work guiding mechanism including a sewing cam shaft, a curved hook needle, a needle actuating cam lever, a needle threading device, a welt guide, a welt knife supported from the welt guide and arranged to sever the welt adjacent the welt guide, means operable upon stopping the machine for advancing and retracting the welt knife, a thread gripping and cutting mechanism arranged to grip the thread extending from the work, a connection actuated by the advancing movement of the welt knife to cause the thread gripping and cutting mechanism to grip and to sever the thread from the work, and a connection actuated from the needle cam lever operable upon starting the machine for actuating the thread gripping device to release the thread subsequent to the threading of the needle by the threading device.

22. In an inseam shoe sewing machine, the combination of shoe sewing mechanism comprising a sewing cam shaft, a curved hook needle arranged to enter the work from the sole side for laying the successively formed chain loops of the seam on the sole, a needle actuating cam lever, a

needle threading device, a thread gripping and severing device arranged to grip the thread extending from the welt side of the work and to sever the gripped thread from the work, means operative upon stopping the machine for actuating said thread gripping and severing device, and a connection actuated from the needle cam lever for actuating the gripping device to release the thread during the loop drawing stroke of the needle.

23. In an inseam chainstitch shoe sewing machine, the combination of shoe sewing mechanism including a curved hook needle arranged to enter the work from the sole side for laying the successively formed chain loops of the seam on the sole, a needle threading device, a driving and stopping mechanism for the sewing mechanism, a welt guide, means for severing the welt from the work at the side of the needle with the welt guide and for advancing the severed end of the welt through the welt guide, a thread gripping and severing device arranged to grip the thread extending from the welt side of the work and to sever the gripped thread from the work, and means operative upon stopping the machine for actuating each of said means for severing and advancing the welt, and said thread gripping and severing device.

24. In an automatic inseam chainstitch shoe sewing machine, the combination of a shoe supporting jack, automatic means for imparting positioning and feeding movements to the jack to transfer the point of operation about the sole margin of a shoe, shoe sewing mechanism including a curved hook needle arranged to enter the work from the sole side for laying the successively formed chain loops of the seam on the sole, a needle threading device, a driving and stopping mechanism for the machine including an auxiliary mechanism actuated by said automatic means at the completion of a seam for the performance of certain operations after the machine has stopped, a welt guide, means for severing the welt from the work at the side of the needle with the welt guide and for advancing the severed end of the welt through the welt guide, a thread gripping and severing device arranged to grip the thread extending from the welt side of the work and to sever the gripped thread from the work, and means controlled from said auxiliary mechanism for actuating each of said welt severing and advancing means and said thread gripping and severing means.

25. In an automatic inseam chainstitch shoe sewing machine, the combination of a shoe supporting jack, automatic means for imparting positioning and feeding movements to the jack to transfer the point of operation about the sole margin of a shoe, shoe sewing mechanism including a curved hook needle arranged to enter the work from the sole side for laying the successively formed chain loops of the seam on the sole, a needle threading device, a driving and stopping mechanism for the machine, a welt guide, a welt severing knife arranged to sever the welt from the work at the side of the needle with the welt guide, a welt advancing finger arranged for advancing the severed end of the welt through the welt guide, a thread gripping and severing device arranged to grip the thread extending from the welt side of the work and to sever the gripped thread from the work, and means operative upon stopping the machine for actuating each of said welt severing knife, welt advancing finger and thread gripping and severing device.

26. In an automatic inseam chainstitch shoe sewing machine, the combination of a shoe supporting jack, automatic means for imparting positioning and feeding movements to the jack to transfer the point of operation about the sole margin of a shoe, shoe sewing mechanism including a curved hook needle arranged to enter the work from the sole side for laying the successively formed chain loops of the seam on the sole, a needle threading device, a driving and stopping mechanism for the machine including an auxiliary mechanism actuated by said automatic means at the completion of a seam for the performance of certain operations after the machine has stopped, a welt guide, a welt severing knife arranged for severing the welt from the work adjacent the welt guide, a welt advancing element arranged for advancing the severed end of the welt through the welt guide, a thread gripping and severing device arranged to grip the thread extending from the welt side of the work and to sever the gripped thread from the work, and means controlled from said auxiliary mechanism for actuating each of said welt severing knife, welt advancing element and thread gripping and severing device.

27. In an inseam chainstitch shoe sewing machine, the combination of a shoe sewing mechanism including a curved hook needle arranged to enter the work from the sole side for laying the successively formed chain loops of the seam on the sole, a needle threading device, a driving and stopping mechanism for the sewing mechanism, a welt guide, a welt severing knife arranged to sever the welt at the side of the needle with the welt guide, and a thread gripping and severing device arranged to grip the thread extending from the welt side of the work and to sever the gripped thread from the work, and means operative upon stopping the machine for actuating the welt knife and thread gripping and severing device.

28. In an inseam chainstitch shoe sewing machine, the combination of stitch forming mechanism including a curved hook needle arranged to enter the work from the sole side for laying the successively formed chain loops of the seam on the sole, a needle threading device, a driving and stopping mechanism for the sewing mechanism, a welt guide, a welt severing knife arranged to sever the welt at the side of the needle with the welt guide, an element arranged to engage and to advance the severed welt through the welt guide, actuating mechanism for the welt severing knife and welt advancing element, a thread gripping and severing device arranged to grip the thread extending from the welt side of the work and to sever the gripped thread from the work, and means controlled from said actuating mechanism for actuating the thread gripping and severing mechanism.

29. In a chainstitch shoe sewing machine, the combination of a curved hook needle, a take-up, a thread finger, a looper having a looper eye, a shank portion and additional guiding means for guiding the thread along the shank portion of the looper to the looper eye, and thread friction means mounted on said shank portion for frictioning the thread extending from said guiding means to the looper eye.

30. In a chain stitch shoe sewing machine, the combination of a curved hook needle, a take-up, a thread finger, a looper having an open eye for ease of threading, and thread frictioning means supported in fixed relation to the looper eye for

frictioning the thread extending from the take-up to the looper.

31. In a chainstitch shoe sewing machine, the combination of a curved hook needle, a take-up, a thread finger, a looper having a shank portion and an open eye for ease of threading, and frictioning means for the thread carried on the shank portion of the looper for frictioning the thread extending from the take-up to the looper eye.

32. In a chainstitch shoe sewing machine, the combination of a curved hook needle arranged to enter the work from the channel side, a take-up, a thread finger, a looper having an eye for positioning the thread with respect to the needle, and thread guiding and frictioning means fixedly supported with respect to the looper eye for frictioning the thread extending from the take-up to the looper eye.

33. In a chainstitch inseam shoe sewing machine, the combination of a curved hook needle arranged to enter the work from the channel side, a take-up acting to draw a tight loop of thread around the shank of the needle while the needle is in the work, a thread finger, a looper having an open eye for ease of threading and a flattened shank portion adjacent thereto, guiding means for guiding the thread across said flattened portion to the looper eye, and spring frictioning means engaging the thread against said flattened portion.

34. In an inseam sewing machine, the combination of sewing mechanism including a sewing cam shaft, a curved hook needle, a needle threading device, a thread tensioning device, a driving and stopping mechanism for the sewing cam shaft, means operative in stopping the machine to release the thread tension, and means operative in starting the machine to re-establish said thread tension only after the sewing of a plurality of the initial stitches of the new seam.

35. In an inseam shoe sewing machine, the combination of sewing mechanism including a sewing cam shaft, and stitch forming devices including a curved hook needle, a needle threading device, a thread take-up, suitable connections for actuating said devices including an actuating element to which is imparted a movement to and fro by said cam shaft during each stitch forming cycle, a thread tensioning device, a driving and stopping mechanism for the sewing cam shaft, means operative in stopping the machine to release the thread tension, and means operative in starting the machine to re-establish said thread tension comprising connections so arranged as to be rendered operative by a plurality of the to and fro movements of said actuating element to re-establish said thread tension only after the forming of a plurality of the initial stitches of a new seam.

36. In an inseam shoe sewing machine, the combination of sewing mechanism comprising a sewing cam shaft, a curved hook needle, a needle threading device, a thread take-up, a take-up lever, a thread tensioning device, a driving and stopping mechanism for the machine, means operative in stopping the machine to actuate the thread tensioning device to release the thread tension, a locking arm connected to support the tension device in tension release position, and

70 a latch having a plurality of supporting notches thereon for engagement alternatively with the locking arm to maintain the thread tensioning device in a released condition, and a trip element arranged to be acted upon by the take-up lever during its loop drawing and return movement for

oscillating the latch, whereby the locking arm is engaged successively with said notches and is then released to re-establish the tension on the thread only after the forming of a plurality of the initial stitches of the seam.

37. In an inseam shoe sewing machine, the combination of sewing mechanism comprising a sewing cam shaft, a curved hook needle, a needle threading device, a thread take-up, a take-up lever, a thread tensioning device, a driving and stopping mechanism for the machine including a stop motion clutch, and an element to which

motion is imparted for controlling the said clutch to stop the cam shaft, a connection actuated by the motion of said element in stopping the machine to actuate the thread tension to release the thread, a latch mechanism for supporting said thread tension device in its released position, and means rendered operative only by a plurality of loop drawing and return movements of said take-up lever for actuating said latch mechanism to re-establish the tension on the thread.

ALFRED R. MORRILL.
